DESIGN FOR A DECK OF PLAYING CARDS

Amelia Poggi, Doris Jordan, and Alma Chuka,
Hicksville, N. Y.

Application July 14, 1945, Serial No. 120,695

Term of patent 7 years

(Cl. D34—13)

To all whom it may concern:

Be it known that we, Amelia Poggi, Doris Jordan, and Alma Chuka, citizens of the United States, residing at Hicksville, in the county of Nassau and State of New York, have invented a new, original, and ornamental Design for a Deck of Playing Cards, of which the following is a specification, reference being had to the accompanying drawings, forming part thereof.

In the drawings, Figures 1 and 2 are face views of a deck of playing cards showing our new design.

The reverse side of each playing card is blank and each card is of conventional thickness.

We claim:

The ornamental design for a deck of playing cards, substantially as shown and described.

AMELIA POGGI.
DORIS JORDAN.
ALMA CHUKA.
